HYDRAULIC HYDRANT DISASSEMBLY WRENCH

David F. Thomas, West St. Paul, Minn., assignor to Waterous Company, Ramsey County, Minn., a corporation of Minnesota

Application April 19, 1954, Serial No. 423,992

9 Claims. (Cl. 29—240)

This invention relates to an improvement in hydraulic disassembly wrench and deals particularly with a wrench useful in removing hydrant valve seats.

The hydrants which are of the type used in colder climates are usually extended down into the ground at substantial distance. A hydrant valve is provided at the lower end of the hydrant by means of which the water from the water main may be directed into the interior of the vertical hydrant. A valve stem normally extends downwardly through the center of the hydrant by means of which the valve may be opened or closed. This valve stem usually extends into a hydrant top or bonnet and engages an operating nut. By rotating the operating nut by means of a suitable wrench, the valve stem may be moved vertically.

The valve assembly is constructed so that it may be taken apart for repairs without disturbing the hydrant. The removable portion of the valve assembly is provided with a pair of oppositely disposed upwardly extending lugs. By providing a pipe with a jaw at one end notched suitably to accommodate the lugs on the valve assembly, and by sliding this pipe down over the valve stem, the valve assembly may be engaged for rotation. By rotating this pipe the valve assembly may be loosened and removed.

While the valve assemblies may be easily removed when the hydrants are serviced at regular intervals, it is commonplace for the valve assemblies to remain intact for a considerable period of years. As a result the valve assemblies become affixed in place so firmly so that considerable torque is required to unthread them. The present device comprises a tool designed to assist in this valve assembly removal operation.

An object of the present invention resides in the provision of a disassembly tool which includes a base plate designed for attachment to the hydrant so as to extend in a generally radial direction therefrom. This base plate is designed to fit onto the body of the hydrant after the cap or bonnet of the hydrant has been removed. A wrench is provided which engages about the pipe, said pipe encircling the valve stem and secured to the jaw which engages the lugs on the valve assembly. The wrench is provided with a lever which extends in a generally radial direction. A hydraulic cylinder is pivotally supported at the extremity of the base plate and is pivotally connected to the wrench lever. By providing suitable hydraulic pressure for this cylinder, the wrench arm may be rotated, thus exerting a rotative force upon the pipe which in turn acts to unthread the valve assembly.

A feature of the present invention resides in the simplicity of construction and operation of the device. The entire apparatus may be made at a relatively low price and is extremely simple in nature. As a result it may be conveniently moved from place to place by the person or persons repairing the hydrant and at the same time is capable of exerting sufficient rotative force upon the pipe to disengage valve assemblies even though they

2

have remained in place for a considerable period of years.

A further feature of the present invention lies in the compactness of the present structure. The present device is compact in form but yet is capable of accomplishing the same work as a wrench having a handle of considerable length.

These and other objects and novel features of the present invention will be more clearly and fully set forth 10 in the following specification and claims.

In the drawings forming a part of the specification:

Figure 1 is a top plan view of the hydrant assembly and disassembly wrench, showing the relationship of parts therein.

Figure 2 is a side elevational view of the structure shown in Figure 1, a portion of the structure being shown in cross section.

Figure 3 is a perspective view of the lower end of the valve assembly and disassembly tool showing in general 20 the arrangement thereof.

In the drawings a portion of a hydrant is diagrammatically illustrated in Figure 2, the hydrant being designated in general by the letter A. The hydrant is shown as having a vertical sleeve 10 provided at its upper extremity with a peripheral flange 11. This flange includes a series of angularly spaced apertures 12 designed to accommodate bolts such as 13 which act to hold the bonnet or cap of the hydrant in place. This bonnet or cap has been removed from the hydrant as it is disclosed in 30 Figure 2.

The hydrant A also includes a valve stem 14 which extends axially through the sleeve 10 and which projects into the bonnet. By operating the valve stem 14, the valve at the lower end of the hydrant may be opened 35 to permit liquid to flow into the hydrant casing.

While not shown specifically in the drawings, the valve assembly at the lower end of the hydrant is usually provided with upwardly projecting angularly spaced lugs which may be engaged by a suitable tool for rotating 40 the entire valve assembly so as to disengage this valve assembly for repair or replacement. As the hydrant usually is quite long and extends a considerable distance into the ground, the valve assembly is usually disengaged by a suitable tool, portions of which are shown in Figures 2 and 3 of the drawings and which is indicated in 45 general by the letter B. The tool B includes an elongated tubular sleeve 15 of proper interior diameter to encircle the valve stem 14, which sleeve 15 is provided with a jaw 16 at its lower extremity. The jaw 16 is provided with angularly spaced notches 17 which correspond in 50 spacing to the lugs on the valve assembly so that the jaw will engage the valve assembly lugs. When the lugs are engaged in the notches 17, the sleeve 15 may be rotated to rotate the valve assembly to unthread it from the valve housing.

In order to provide a means of readily rotating the sleeve 15, a hydraulic disassembly wrench is provided which is indicated in general by the letter C and which forms the subject of the present invention. This wrench 55 C includes a base plate 19 having an end portion 20 which is provided with an aperture 21 therethrough of sufficient size to freely encircle the sleeve 15. For convenience in mounting the base plate 19 I provide a slot 18 which extends radially through the base plate communicating with the central aperture 21 so that the tool may be mounted upon the top of the hydrant body without lifting it sufficiently to extend over the upper end of the sleeve 15. Due to the fact that hydrants may be made in a variation of lengths, the sleeve 15 may extend 60 considerably above the tops of the bodies of certain hydrants.

The portion 20 of the base plate 19 which encircles the sleeve 15 is provided with a plurality of angularly spaced apertures indicated by the numeral 22. In view of the fact that hydrant bodies may vary in diameter and in view of the further fact that the bolt apertures 12 of the hydrant body flanges 11 may vary in their angular spacings, apertures 22 are arranged in concentric rings of apertures, the apertures of each concentric ring being designed to register with the bolt holes 12 of a hydrant of a particular diameter. The base plate 19 extends outwardly from the hydrant in a generally radial direction and the side edges of the base plate are provided with downturned flanges 23 and 24 which act to reinforce the arm and make it more rigid.

The sleeve encircling portion of the wrench may be varied somewhat in design, the particular form of construction illustrated being found very advantageous for the purpose. This portion of the wrench includes a rounded segment 25 which is provided with an arcuate inner edge 26 provided with teeth 27. This segment 25 is provided with a projecting tongue 29, straddled by the bifurcated end 30 of a second curved segment 31. A pivot 32 extends through the overlapping tongue 29 and bifurcated end 30 so as to pivotally connect these parts.

The segment 31 is provided with an arcuate inner surface 33 which is provided with angularly spaced teeth 34. The articulation of the segments 25 and 31 is equal so that these two segments may engage snugly about the sleeve 15. The two segments cooperate by gripping the sleeve during rotation.

The lever 35 is pivotally attached at 36 to an end of the segment 31 and is attached intermediate its ends at 37 to the end of the segment 25. The end of the segment 25 is bifurcated as illustrated at 39 to accommodate the lever 35 and the segment 31 is also provided with a bifurcated end 40 which accommodates the end of the lever 35. As is clearly shown in Figure 1 of the drawings, the point of connection of the lever 35 with the segment 31, related to the point of connection of the lever with the segment 25, is such that if force is exerted upon the free end of the lever 35 tending to rotate this lever in a counter clockwise direction, the two segments are wrapped firmly about the sleeve 15 tending to rotate the sleeve 15. The movement of the lever 35 in a clockwise direction pivots the segments 25 and 31 apart to the extent necessary to connect the free rotation of these segments relative to the sleeve 15. An angle bracket 41 is secured to the end of the base plate 19 by welding or by other suitable means, the bracket 41 having a vertical flange 42 and a horizontal flange 43 which is parallel to the plane of the base plate 19. A hydraulic cylinder 44 is pivotally connected between the bracket 41 and the free end of the lever arm 35. The cylinder 44 is provided with a piston rod 45 which extends into the cylinder 44 and may be either provided with a piston at its inner end or may in itself serve as a piston. The rod or plunger 45 is slideable within the cylinder 44. A head or coupling 46 is mounted upon the piston rod 45, this coupling being provided with a bifurcated end 47. This bifurcated end 47 straddles the free end of the lever 35 and a pivot pin 49 extends through the bifurcated end 47 and through the lever 35 to pivotally connect the piston rod 45 to the lever 35.

The cylinder 44 is provided with projecting end 50 which extends between the horizontal flange 43 of the angle bracket 41 and the base plate 19. A pivot pin 51 extends through the flange 43, the cylinder end 50, and the base plate 19 to pivotally anchor the cylinder to the free end of the base plate 19. A spacer sleeve 52 encircles the pivot 51 beneath the cylinder end 50 so as to hold the cylinder at the proper elevation.

A small hydraulic pump 53 is supported upon the base plate 19. This pump 53 may be of any suitable type to supply fluid pressure to the cylinder 44. In the particular

form illustrated the pump includes a pump body 54 having a pump handle 55 which is capable of reciprocating a plunger to force fluid through the flexible connector 56 to the fitting 57 at the end of the cylinder 44. If preferred, the pump may be of the double acting type which may either force fluid into the cylinder or force fluid out of the cylinder.

Figure 1 of the drawings discloses a spring 60 which connects the lever 35 to a reinforcing rib 61 on the base plate 19. This spring is optional, and is omitted in Figure 2 for the purpose of clarifying the remaining structure. In the event the pump 53 is of the single acting type, the spring 60 may be used to return the lever 35 to starting position. As the piston rod or plunger 45 is forced from the cylinder 44, the spring 60 is expanded. When the lever 35 has reached the end of its movement in a counter clockwise direction, the fluid pressure from the pump 53 may be released in any suitable way, as by a valve controlling the flow of fluid to the reservoir. When the hydraulic fluid is free to travel in a reverse direction, the spring will draw the lever 35 in a clockwise direction. By controlling the reverse flow, the speed of reverse rotation can be varied.

The operation of the apparatus is believed quite evident from the foregoing description. When the valve assembly of the hydrant is to be removed, the cap or bonnet of the hydrant is removed by removing bolts such as bolts 13. The tool B is next applied by inserting the tube 15 over the valve stem 14 and sliding the tool downwardly until the jaw 16 rests upon the valve assembly. The jaw is then rotated until the lugs of the valve assembly become engaged in the notches 17.

The apparatus C is next attached to the top of the hydrant body. The wrench portion of the device is opened up by removing the pivot 37 which may be in the form of a bolt or pin. The two segments 25 and 31 of the wrench are swung open and the base plate 19 is moved laterally, the sleeve 15 entering the slot 18 until it is concentric with the aperture 21 of the base plate. Bolts 13 are then used to secure the baseplate to the top of the hydrant body.

The wrench portions are then closed about the sleeve 15 and the pivot 37 reinserted. This section normally takes place when the plunger 45 is fully retracted. The pump 53 is then operated to supply fluid under pressure through the conduit 56 and fitting 57 into the cylinder 44, moving the plunger outwardly.

This movement swings the lever 35 in a counter clockwise direction, the lever acting to wrap the wrench sections tightly about the sleeve 15. Further pivotal movement of the lever 35 rotates the sleeve 15 in a counter clockwise direction, unthreading the valve assembly from its housing.

After the valve assembly has been loosened to some extent the sleeve 15 usually may be rotated without the hydraulic device. However, if further rotation by the hydraulic wrench is required the fluid may be withdrawn from the cylinder 44 to return the lever 35 to its starting position. During this action the lever 35 loosens the wrench portions so that they do not rotate the sleeve 15 in unison with the wrench. Any desired number of strokes may be employed to loosen the valve assembly, it being usually necessary to only rotate the valve seat a relatively small amount to free it from the housing. After the valve seat has been loosened, the bolts 13 are removed and the base plate 19 taken out of operative position. The pivot 37 is removed to open the wrench for this purpose.

The device can be used in a reverse direction if the cylinder 44 is of the double acting type. In such an event the wrench is inverted from the position shown so that the lever 35 will tighten the wrench portions when the lever is pulled in the opposite direction. Usually, however, it is not necessary to employ the hydraulic

cylinder for tightening the valve assembly as it can be usually tightened with ordinary tools.

In accordance with the patent statutes, I have described the principles of construction and operation of my hydraulic disassembly wrench, and while I have endeavored to set forth the best embodiment thereof, I desire to have it understood that obvious changes may be made within the scope of the following claims without departing from the spirit of my invention.

I claim:

1. A portable hydraulic hydrant disassembly wrench assembly for attachment to a hydrant and use in rotating an attachment to an inner valve member with respect to an outer enclosing member, the wrench assembly including in combination a base plate attachable to a hydrant, a plurality of attachment means for securing the base plate to different sized outer enclosing members to extend and hold the base outwardly therefrom as a support, a grip wrench arranged to encircle said attachment to the inner valve member and rotate the same upon rotation of the wrench, and an expandable and contractable hydraulic cylinder connected to said base plate and to said wrench to rotate the wrench upon expansion or contraction of said cylinder.

2. The structure described in claim 1 and including parallel pivots connecting the ends of said cylinder to said wrench and in spaced relation to said base plate respectively.

3. The structure described in claim 1 and in which the base plate is slotted to accommodate the inner member and provided with apertures for bolting to the outer enclosing member.

4. The structure defined in claim 1 and in which the base plate extends substantially radially from the inner member and the outer member.

5. A hydraulic disassembly wrench assembly for use in disassembling a hydrant valve assembly within a hydrant casing, the wrench including in combination a base plate platform having an end designed for attachment to a hydrant casing for supporting said wrench as-

sembly, said end having an opening therein for accommodation of a rotatable sleeve, adjustable sized attaching means holding said base plate extending laterally from the hydrant casing top, a wrench engageable with a rotatable sleeve connected to said valve within said casing, a fluid cylinder having a plunger in telescoping relation thereto secured to said base plate and supported thereby, means for supplying fluid under pressure to move said plunger, said cylinder and plunger forming an expandable and contractable member, means connecting one end of said member to said base plate laterally of said casing, and means connecting the other end of said member to said wrench, whereby movement of said member oscillates said wrench.

15 6. The structure described in claim 5 and including parallel pivots forming the means connecting said member to said base plate and to said wrench.

20 7. The structure described in claim 5 and in which the end of said base plate designed for attachment with a hydrant body includes about an open mounting slot and aperture a series of angularly spaced apertures through which said holding means may extend.

25 8. The structure described in claim 5 and including resilient means urging said wrench in one rotative direction.

9. The structure described in claim 5 and including resilient means connecting said wrench and said base plate and urging said wrench in one rotative direction.
